COMBINED HEADLAMP BEZEL AND GRILLE

George W. Walker, Bloomfield Hills, Mich., assignor to Ford Motor Company, Dearborn, Mich., a corporation of Delaware

Filed Nov. 25, 1960, Ser. No. 62,967

Term of patent 7 years

(Cl. D14—6)

Fig. 1 is a front view of a combined headlamp bezel and grille, showing my new design;

Fig. 2 is a top plan view; and

Figs. 3, 4, 5 and 6 are sectional views taken on the planes indicated by lines 3—3, 4—4, 5—5 and 6—6 of Fig. 1.

I claim:

The ornamental design for a combined headlamp bezel and grille, substantially as shown.
